(57) **CLAIM**

The ornamental design for a grill pan trivet, as is shown and described herein.

DESCRIPTION

FIG. 1 is a perspective view of a grill pan trivet showing our new design;

FIG. 2 is a bottom plan view thereof;

FIG. 3 is a top plan view thereof;

FIG. 4 is a right side elevational view thereof; the left side elevational view thereof being a mirror image thereof; and, FIG. 5 is a front elevational view thereof; the rear elevational view being a mirror image thereof.

The broken lines shown in the drawings are for illustrative purposes only and form no part of the claimed design.
